CLAIM

The ornamental design for a fluid coupling as shown and described.

DESCRIPTION

FIG. 1 is a top and front perspective view of a fluid coupling.

FIG. 2 is a front elevation view thereof;

FIG. 3 is a rear elevation view thereof;

FIG. 4 is a left-side view thereof;

FIG. 5 is a right-side view thereof;

FIG. 6 is a top plan view thereof; and,

FIG. 7 is a bottom plan view thereof.

The evenly spaced broken lines depict portions of the fluid coupling that form no part of the claimed design. The dash dot dash broken lines depict unclaimed portions of the fluid coupling and also depict the boundaries of the claim which form no part thereof.

1 Claim, 4 Drawing Sheets
